UNITED STATES PATENT OFFICE.

CHARLES J. KINDEL, OF CHICAGO, ILLINOIS.

FOLDING BED.

1,120,942.

Specification of Letters Patent. Patented Dec. 15, 1914.

Application filed February 26, 1913. Serial No. 750,931.

To all whom it may concern:

Be it known that I, CHARLES J. KINDEL, a citizen of the United States, residing at Chicago, in the county of Cook and State of Illinois, have invented new and useful Improvements in Folding Beds, of which the following is a full, clear, concise, and exact description, reference being had to the accompanying drawing, forming a part of this specification.

My invention relates to improvements in folding couches or davenport's and the object of my invention is the provision of improved means whereby the back section may be adjusted or swung to a position in which it will be out of the way when the sections are unfolded and held or locked in such a position.

A further object of my invention is the provision of means whereby the back section may be supported or folded into the casing, if desired, when the sections are unfolded for use.

A further object of my invention is a provision of means whereby the mattress may be held locked in position and also means whereby said retaining means may be used as a foot board.

A further object is the provision of means whereby the legs and operating means therefor may be concealed within the frame and in the rear of the back when such device is used as a divan.

A further object is the production of an improved, simple, durable and compact device that can be cheaply manufactured and also one that may be easily operated.

These and such other objects as may hereinafter appear are attained by my device, embodiments of which are illustrated in the accompanying drawings, in which:

Figure 1 represents a longitudinal view of a bed embodying my invention showing the parts in folded position; Fig. 2 represents a detail view partly in section showing the back section in raised position. Fig. 3 is an end view of Fig. 2 with parts broken away. Fig. 4 is a perspective view of one of the details of my device. Fig. 5 is a detail view partly in elevation and partly in section showing the back section folded into the frame. Fig. 6 shows a plane view of the portion of the foot section with the mattress retainer in closed position, the open posi-

tion being indicated by dotted lines; and Fig. 7 represents a plane view of Fig. 6.

Like numerals indicate like parts in the several figures in the drawings.

Referring now to the drawings, 10 designates generally the frame having sides 10^a and a back 11, preferably extending above the top of the sides. Arranged so as to fold into and out of the frame thus formed are preferably three sections, a head section 12, an intermediate section 13 and a main section 14, the section 12 being supported at one end at a link 15 pivotally connected to the section and to the frame at 15^a, and is supported at its other end by means of a pivot 16 formed between the sections 12 and 13. The section 13 is supported by means of a fixed pivot 17, which also forms the pivotal point about which the main section 14 swings.

The seat 18 is connected with the foot section 14 by means of links 19 so that the seat will fold upon the section 14 when the latter is in a folded position as shown in Fig. 1. The seat will depend from the section 14 when the latter is swung about the pivot 17 during the unfolding operation and the section 14 is brought into position to be used as part of the bed frame.

Supporting legs 20 are provided for the lower end of the foot section 22 and these legs are connected by means of links 21 to the section in such a manner that when the section is unfolded the legs 20 will be forced or guided into position to support the lower end of the section and when the section 22 is folded up the legs 20, together with their operative links, will be folded into position shown in Fig. 1 within the frame and back of the seat section, being thereby hidden entirely from view and in a position from which they are readily turned into place on opening the device.

The folding back section 23 is supported by means of pairs of links 24—25 pivotally connected at one end to the section. The other ends of the lower links 24 are pivotally connected as at 26 to the outer portion of another link 27 and the free ends of these links 27 are preferably curved, as shown in Figs. 2 and 5 and are pivotally connected as at 28 to a bracket 29, arranged within the back 11, preferably at the top. The other end of the link 25 is pivotally connected at

30. with the link 27 intermediate the ends of the latter and these links 24—25 serve as means for causing the back section 23 to have a substantially parallel movement with respect to link 27 when the two are swung about the pivots 28. Another pair of links 31 is pivoted as at 32 to each of the links 25 intermediate the pivots of the latter and the outer end of these links 31 are also 10 curved as shown and are pivotally connected as at 33 to the brackets 29. It will thus be seen that the back section 23 may be raised and lowered from the position shown in Fig. 1 to the position shown in Fig. 2. 15 and during such raising movement, the links 27—31 will move about their pivots 28—33 to cause the back section to assume the position shown in Fig. 2. In order to maintain the back section in this elevated position any suitable mechanism may be provided;—a simple and efficient means comprising a plate or a pair of plates 34, preferably one on each side of the frame. Each of these plates is provided with an L shaped 20 slot having a horizontal portion 35 and an upright portion 36 and the plate itself is pivotally connected as at 37 with a bracket 39.

In Figs. 6 and 7 are illustrated the mattress retaining means, by means of which the mattress is held securely in position on the foot section. This comprises a pair of swinging arms 40 preferably curved and pivoted at 41 on U frames 42, mounted on the foot section having an end vertical flange 50 and lateral flanges 48. These arms are parallel and are connected at their end in any suitable manner as by a board 43 held in position between the arms by means of screws 44. Of course, it is evident that in place of a board, I could use wires if desired. Swingly mounted on the arms 40 at 45 are locking members 46 provided with a pair of pins 47 adapted to engage the top 48 of the plate 42, holding the arm in the position indicated, in Fig. 6, the end 49 of the arm striking against the upright end 50 of the frame. On each of the arms 40 is mounted a pin 51 adapted to strike against the top 50 of the frame, preventing the arms from falling backward when it is desired to raise the same and permit it to constitute a foot board, in which event the pin 51 strikes the top of the frame as shown by dotted lines 55 in Fig. 6. When it is desired to raise the arms and retaining member, it is simply necessary to swing up the locking member 46 above the top and end of the frame and then swing the arms 40 backward on the pivot 41. The lock will then assume the position shown in dotted lines in Fig. 6.

Each of the links 27 is provided with a laterally projecting lug or pin 38 which projects into the slots in their respective places 60 and these slots are so positioned in the plate

itself that when the back section has been moved into the position shown in Fig. 2, the plates 34 may be swung in their pivots either manually or automatically and cause the pins to enter the upright portions 36 of the slots, the link 31 co-operating with this locking plate or member 34 to lock the back section in this raised position. When it is desired to lower the back section 23, all that is necessary to do is to swing the plates 34 about their pivots so that the pins 38 enter the long slot 35, permitting the plates 34 to swing about their pivots.

In the event that it is not desired when the seat section 18 is unfolded, to raise the section 23, it may be folded into the back 11, as shown in Fig. 5 by simply forcing the lower edge of the section backwardly, the parts being so arranged that it will automatically fall in this position, as clearly shown in the above mentioned figure.

In order to prevent the back section from being moved into the folded position within the back of the frame when the seat 18 is in use, suitable stops 39 are provided on the back edge of the seat 18 and these stops 39 occupy positions within the path of the free edge of the back section while it is being folded and thus this edge will engage the stops as shown in Fig. 1.

Conditions may arise or the individual opinions of the users may be such that some may prefer the back raised and out of the way when the device is used as a bed while others may prefer the back down and pushed into the frame as shown in Fig. 5. The housing of the legs and their operating links behind the back frame leaves a greater amount of space within the bottom of the frame for the reception of the mattress and bed coverings.

While I have described and shown certain means for accomplishing results desired it is understood that these same results may be attained by other means without departing from the spirit of my invention.

Having thus fully described my invention, what I claim as new and desire to obtain by Letters Patent is:

1. In a folding bed the combination with a frame, bed sections, a movable back normally in position to be used as a back rest, and means for causing said back to rotate into a position out of the way above or within said frame, and means for locking said back when in raised position.

2. In a folding bed the combination of a frame, a plurality of bed sections, a back section supporting means for the outermost of said sections adapted to move upwardly and forwardly and means whereby said outermost section and its supports may be concealed within said frame.

3. In a folding bed the combination of a frame, a plurality of bed sections adapted

to move upwardly and forwardly, a back section supporting means for the outermost of said sections and means whereby said outermost section and its supports may be concealed behind said back.

4. In a folding bed, the combination with a frame, a movable back and lever connections with the top of said frame whereby said back may be swung either above or within said frame at will, a single plate secured at the top of said frame provided with angular slot, hinge connections on one of said levers adapted to slide in said slot and lock said back in raised position.
5. In a folding bed, a combination of a frame, a plurality of bed sections, a back section and means for swinging said back section either above or within said frame, said means comprising a plate rigidly mounted on said frame, a swinging link mounted thereon, an upper and lower link connection between the back and said swing-
- 10
- 15
- 20
- 25

ing link, a second swinging link mounted on said plate and secured at its lower end to said upper link intermediate to its points of attachment and means for locking said back to an upright position.

6. In a folding bed the combination with a frame, a plurality of bed sections, a back section, means for swinging said back section either above or within said frame and locking said back in raised position, said means comprising a series of swinging links, a plate provided with an angular slot, and means mounted on one of said links to engage said slot.

In witness whereof, I have hereunto subscribed my name in the presence of two witnesses.

CHARLES J. KINDEL.

F. H. DRURY,
ANNE SOLOMON.

It is hereby certified that in Letters Patent No. 1,120,942, granted December 15, 1914, upon the application of Charles J. Kindel, of Chicago, Illinois, for an improvement in "Folding Beds," errors appear in the printed specification requiring correction as follows: Page 2, line 124, after the word "section" insert the words *adapted to move upwardly and forwardly*; same page, lines 125-126, strike out the words "adapted to move upwardly and forwardly"; and that the said Letters Patent should be read with these corrections therein that the same may conform to the record of the case in the Patent Office.

Signed and sealed this 16th day of February, A. D., 1915.
